DRILL ROD

William B. Peirce, Pittsburgh, Pa., assignor to
Flannery Bolt Company, Bridgeville, Pa., a corporation of Delaware

Application June 9, 1943, Serial No. 490,194

1 Claim. (Cl. 15—104.16)

This invention pertains to a percussion drill and is for a drill rod of this type specifically designed for removing from the tell-tale holes of boiler staybolts impactions of foreign matter which must be dislodged before the bolt, or the boiler in which the bolt is used, can be tested.

The staybolts in locomotive boilers are commonly provided with an axially extending hole of small diameter, this hole terminating short of the outer end or head of the bolt and opening through the end of the bolt at the fire-box end. Notwithstanding the use of porous plugs in the open ends of the holes, fine dust, scale and other materials become compacted in the holes, especially in some locations in the boiler. Since the purpose of the tell-tale hole is to disclose a fracture in the bolt when the boiler is put under hydrostatic test by permitting water to escape at the fire-box end of a ruptured bolt when the boiler is tested, it is apparent that any impaction must be cleared away before the tell-tale hole can serve its purpose or the boiler adequately be tested.

This is accomplished by the use of a long, slender percussion drill not generally unlike a rock drill, the drill being rapidly reciprocated by an appropriate air or other hammer. Air is discharged through a tiny bore in the drill bit to carry away the cuttings or dust dislodged by the drill. It will be apparent that the diameter of the drill must be less than the diameter of the tell-tale hole while the length must be relatively great, the bolts in some instances being more than thirty-six inches long.

Two outstanding difficulties have been encountered which it is the purpose of this invention to substantially eliminate. The first of these is the rapid breakage of the slender shank of the bit where it is joined to the holder at the outer end of the bit, which holder is necessary for securing the bit in the air or other automatic hammer. The second difficulty, which is even more serious, is the clogging of the hole through the bit at the cutter end, especially after one or more sharpenings of the bit.

The clogging of the hole in the bit has been discovered to be incident to the method in which the drill is manufactured, and hence the present invention also provides a method of making the bits to avoid the difficulty. It may be explained that the cutting or bit end of a drill is fluted, and to produce a conventional style of percussive drill, it is required that the fluted end be of larger diameter than the shank of the drill. This has required that the end of the drill rod be upset to expand its diameter. The expanding of the di-

ameter of the bit portion of the drill rod also expanded the diameter of the bore or hole in the upset portion. Then the forging or shaping of the extreme tip of the rod reduced the extreme end of the hole to its original diameter, thereby forming in the bit end of the tool, back of the extreme tip, an elongated pocket or chamber of a diameter greater than the normal bore of the hole. This is initially not ordinarily a source of much trouble, but after one or more resharpenings of the bit, with the grinding away of the tip of the drill, the end of this chamber is opened up, so that there is then an elongated bell-like cavity in the end of the bit, and this fills up quickly with detritus produced in the operation of drilling, cutting off the stream of air through the drill.

Although drills of this kind and for this purpose have been extensively used for many years, a satisfactory remedy for the two defects above noted have not heretofore been found. According to my invention, the upper end of the drill rod, where it enters the adapter or holder, is tapered to an increased diameter. Aside from merely increasing the section of the rod, this tapering of it dampens vibrations along the drill rod in the region of the taper, eliminating the concentration of vibrational stresses at the point where the drill rod is secured in the holder or adapter. The second difficulty is eliminated by a method of forming the drill rod with an enlarged bit portion while maintaining the diameter of the hole uniform. Both of these benefits are obtained by using as stock from which the drill rod is made, a drill rod of a diameter greater than the diameter of the finished rod, and then, instead of upsetting the bit end of the rod, the excess metal between the bit and holder ends is machined away to the ultimate diameter which is required, and at the same time the taper in the shank end is formed by machining.

My invention may be readily understood by reference to the accompanying drawing, in which:

Figure 1 is a side elevation of the drill, showing it entered in the tell-tale hole of a staybolt, the staybolt being shown in section;

Figure 2 is a longitudinal sectional view through the drill, the view being on a larger scale than Figure 1;

Figures 3 and 4 are transverse sections in the planes of lines III—III and IV—IV, respectively, of Figure 2;

Figure 5 is a side elevation of the drill rod at an intermediate stage in its manufacture with the final contour of the drill rod being indicated by dot-and-dash lines;

As most clearly shown in Figure 1, the drill rod has a stem portion 2 of uniform diameter intermediate the end portions thereof. At the tip end of the drill rod the rod gradually increases in diameter toward the free end between points *a* and *b*. At the other end of the drill rod, beginning at the point *c* the drill rod is tapered to increase in diameter toward the end, this taper being in the zone between *c* and *d*, and from *d* to the end of the rod, the rod is cylindrical and larger in diameter than the intermediate part 2. This cylindrical part of the rod, designated 3, is mounted in a drill rod holder 4, being brazed into the holder in the usual way, the holder and the manner of brazing it forming no part of the present invention.

The bit end of the drill rod, i. e., the part 5, between *a* and *b*, is provided with external flutes 6, forming the cutting bit at this end of the rod.

Extending longitudinally throughout the length of the entire rod is a hole 7, which is of uniform diameter throughout its length. Its diameter where it passes through the enlarged bit portion 4 is the same diameter as the hole passing through the slender part 2 of the drill rod. It will be noted that because the hole 7 is of uniform diameter, the bit may be repeatedly sharpened by grinding away portions at the end thereof without changing the size of the opening at the end of the drill. Normally, in a drill of this kind, the bit end is formed by upsetting the metal in the drill rod, and this results in expanding the diameter of the hole through the drill rod. I have discovered that it is this increase in the diameter of the hole that causes these drills to be clogged in use and prevents the escape of the exhaust air which is blown through the hole 7 during the drilling operation.

By providing the part 3 of larger diameter the drill rod is much stronger in cross section at the point where it is brazed into the holder, and therefore, less likely to break at this point, and the gradual taper between *c* and *d* serves to dampen or suppress vibration at this end of the drill rod, whereas if there were an abrupt shoulder between the part 3 of large diameter and the intermediate part 2 of small diameter, the rods would tend to break at such shoulder. Heretofore the outer end of the rods has been of uniform diameter with the part 2, and breakage has occurred where the end of the rod was rigidly joined to the

holder 4. The present invention, through increasing the diameter of the rod where it is engaged in the holder and by providing the tapered part between *c* and *d*, effectively prevents the localizing of vibration to such extent as would cause the breakage of the drill rod.

The drill rod as thus described successfully avoids the two sources of trouble heretofore encountered in rods of this kind, i. e., the clogging of the drill at the bit end and the breaking of the drill at the opposite end.

In order to make the drill, I start by using a tube or rod, the outside diameter of which is equal to the maximum diameter of the parts 3 and 5. I then machine or grind the intermediate part 2 down to its ultimate diameter, and, at the same time, form the tapered surfaces between *a* and *b* and between *c* and *d*. The term "machine" is intended to include any operation of reducing the section of the metal by cutting or abrading, and excludes, of course, any forging or drawing operation. By reference to Figure 5, it will be seen that the diameter of the stock from which the bit is formed is initially uniform, and the dot-and-dash lines show the extent of the machining or grinding operation to produce the finished rod.

I claim as my invention:

A percussive drill rod of long slender proportions such that it is adapted for use in the tell-tale hole 30 of a boiler staybolt, said rod having a long cylindrical intermediate portion of small diameter, a bit portion at one end of the intermediate portion which increases very gradually in diameter from the intermediate portion toward the working end 35 of the bit, said rod having a cylindrical end portion, of larger diameter than the intermediate portion, at its other end, a tapered portion joining the cylindrical portion of large diameter and the intermediate cylindrical portion of smaller 40 diameter, said last named portion increasing very gradually in diameter and a holder permanently secured to said cylindrical end portion of the rod, the tapered portion being spaced from the holder and serving to dampen vibration between the slender intermediate portion and the said cylindrical end portion of larger diameter, the rod having an axially extending hole 45 therethrough the diameter of which is the same in the tapered bit portion as in the shank.

WILLIAM B. PEIRCE.
